(57) **CLAIM**

The ornamental design for a dual screen notebook computer, as shown and described.

DESCRIPTION

FIG. 1 is a front perspective view of the dual screen notebook computer;

FIG. 2 is a back perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right side view thereof;

FIG. 9 is a front perspective view thereof shown in an open position;

FIG. 10 is a back perspective view thereof;

FIG. 11 is a top view thereof;

FIG. 12 is a bottom view thereof;

FIG. 13 is a front view thereof;

FIG. 14 is a back view thereof;

FIG. 15 is a left side view thereof;

FIG. 16 is a right side view thereof;

FIG. 17 is a front perspective view thereof wherein the display panels are shown in an expanded position;

FIG. 18 is a back perspective view thereof;

FIG. 19 is a top view thereof;

FIG. 20 is bottom view thereof;

FIG. 21 is a front view thereof;

FIG. 22 is a back view thereof;

FIG. 23 is a left side view thereof;

FIG. 24 is a right side view thereof;

FIG. 25 is a front perspective view thereof wherein the display panels are shown side by side;

FIG. 26 is a back perspective view thereof;

FIG. 27 is a top view thereof;

FIG. 28 is a bottom view thereof;

FIG. 29 is a front view thereof;

FIG. 30 is a back view thereof;

FIG. 31 is a left side view thereof;

FIG. 32 is a right side view thereof;

FIG. 33 is another front perspective view thereof;

FIG. 34 is a back perspective view thereof;

FIG. 35 is a top view thereof;

FIG. 36 is a bottom view thereof;

FIG. 37 is a front view thereof;

FIG. 38 is a back view thereof;

FIG. 39 is a left side view thereof; and,

FIG. 40 is a right side view thereof.

(Continued)

Broken lines in the drawings are included for the purpose of illustrating an environment only and form no part of the claimed design.

1 Claim, 33 Drawing Sheets
